US0D1047667S

(12) **United States Design Patent** (10) **Patent No.:** **US D1,047,667 S**
(45) **Date of Patent:** **** Oct. 22, 2024**

(54) **SCREEN PROTECTOR APPLICATOR KIT**

(71) Applicant: **Shenzhen Lanhe Technologies Co., Ltd.**, Shenzhen (CN)

(72) Inventors: **Yibo Li**, Shenzhen (CN); **Wei Wei**, Shenzhen (CN)

(73) Assignee: **Shenzhen Lanhe Technologies Co., Ltd.**, Shenzhen (CN)

(**) Term: **15 Years**

(21) Appl. No.: **29/942,076**

(22) Filed: **May 14, 2024**

(30) **Foreign Application Priority Data**

Apr. 7, 2024 (CN) 202430187704.9

(51) **LOC (14) Cl.** **08-05**

(52) **U.S. Cl.**

USPC **D8/14**

(57) **CLAIM**

The ornamental design for a screen protector applicator kit as shown and described.

DESCRIPTION

FIG. 1 is a front perspective view of a screen protector applicator kit showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the screen protector applicator kit that form no part of the claimed design.

1 Claim, 8 Drawing Sheets
